UNITED STATES PATENT OFFICE.

ALFRED G. BIMSON, OF BERTHOUD, COLORADO.

BEET-HARVESTER.

1,169,229.

Specification of Letters Patent.

Patented Jan. 25, 1916.

Application filed July 24, 1915. Serial No. 41,654.

To all whom it may concern:

Be it known that I, ALFRED G. BIMSON, a citizen of the United States of America, and resident of Berthoud, in the county of 5 Larimer and State of Colorado, have invented certain new and useful Improvements in Beet-Harvesters, of which the following is a specification.

This invention relates to harvesters and 10 particularly to beet extractors or harvesters.

An object of this invention is to produce beet lifters which engage opposite sides of the vegetable and dislodge it from the ground, the said invention having for its 15 further object the provision of novel means for regulating the depth of travel of the beet engaging elements and for permitting the adjustment of the said beet engaging elements so that they will have a greater or 20 less tendency to descend under the surface of the earth and increasing or diminishing the depth at which the vegetable is engaged.

A still further object of this invention is to provide removable points which may be 25 readily applied to or removed from the associate members of a beet harvester, it having been found in practice that the points become dull through protracted use and that they sometimes become impaired or broken. 30 By reason of this invention, therefore, the points may be removed for sharpening or for substitution and this has been found to be a comparatively expensive means in the upkeep of implements of this character.

35 With the foregoing and other objects in view, the invention consists in the details of construction, and in the arrangement and combination of parts to be hereinafter more fully set forth and claimed.

40 In describing the invention in detail, reference will be had to the accompanying drawings forming part of this specification wherein like characters denote corresponding parts in the several views, and in 45 which—

Figure 1 illustrates a perspective view of a horse drawn beet harvester, embodying the invention; Fig. 2 illustrates a detail view of a fragment of an extracting bar 50 with the adjustable extensions applied thereto; Fig. 3 illustrates a view similar to Fig. 2 with the parts in different positions of adjustment; and Figs. 4 and 5 illustrate sectional views respectively of the devices 55 shown in Figs. 2 and 3. Fig. 6 is a plan view of the front end, and Fig. 7 a perspec-

tive view of the rear end of removable point 19.

In these drawings 6 denotes a frame, 7 the handles and 8 the draft rigging, all of 60 which is of any ordinary construction and is not described in detail.

The standards 9 are secured to the frame and their lower ends are supplied with extracting bars 10, the purposes of which are 65 well known. In the present invention, the forward ends of the extracting bars are provided with adjustable and removable bars and their correlated parts are of duplicate construction, and a description of one 70 will suffice as a disclosure of the pairs which are utilized in the implement.

It is apparent from an inspection of the drawing that the forward end of each extracting bar has a beveled upper edge 11 75 whereas the lower edge 12 is on the plane of the main portion of the bar. There is a transversely disposed aperture 13 in the said bar for the reception of a pin or bolt 14 by which the sleeve 15 is held on the bar. 80 The sleeve has a socket 16, the upper and lower walls of which taper from the rear end and it is the purpose of the inventor that the socket shall be of such size as to receive the end of the extracting bar. Furthermore the relation of the edges of the 85 extracting bar and the walls of the socket is such that the sleeve may be inverted on the extracting bar and that regardless of the position of the said sleeve on the extracting 90 bar, the edges of the extracting bar will be in engagement with the said sleeve and bar and that according to the position of adjustment of the sleeve on the bar, a greater or less pitch is afforded and this of course 95 will affect the direction of travel of the beet engaging members. The fact that the sleeve may be inverted and with the walls of the socket contacting the upper and lower edges of the extracting bar, insures a strong and 100 durable joint and relieves the securing pin or member of undue strain.

The outer end of each sleeve is further provided with an inwardly tapered socket 17 which receives a tapered shank 18 of the 105 removable point 19. The sleeve has an aperture 20 near its outer end and the shank 18 has an aperture 21 which receives a securing bolt or pin 22 for holding the point in operative relation to the sleeve. One surface of 110 the point is straight as shown at 23 and the opposite surface is beveled as shown at 24

and as the point may be applied to the socket with either the surface 23 or 24 at the bottom, the point and the sleeve may be so assembled as to cause the beet engaging members to have a tendency to descend in the earth and this will insure proper engagement of the members with the said beets; furthermore those surfaces of the point and sleeve which are uppermost will 10 gradually dislodge the beets as they are drawn under it. Aside from the fact that the surfaces of the joint are of the construction indicated for regulating the depth of travel of the point, the surfaces of the shank 15 18 which enter the socket 17 are at different angles from the horizontal so that according to the position of the shank in the socket, the point may be given a greater or less pitch.

By the several adjustments described, the 20 beet extracting members may be set to give the best results under working conditions, which working conditions are affected by the condition of the soil, the size of the beets, etc.

25 I claim

1. In a beet harvester, a frame, standards thereon, extracting bars secured to the standards, said extracting bars having beveled upper edges at the front end forming tapered extensions, sleeves having sockets with upper and lower walls at different angles, said sockets being adapted to receive the ends of the extracting bars and to fit the upper and lower surfaces thereof, said sleeves having tapered sockets in their front ends, and points having shanks fitted to the last mentioned sockets.

2. In a beet harvester, a frame, standards thereon, extracting bars secured to the standards, said extracting bars having beveled

upper edges at the front end forming tapered extensions, sleeves having sockets with upper and lower walls at different angles, said sockets being adapted to receive the ends of the extracting bars and to fit the upper and lower surfaces thereof, said sleeves having tapered sockets in their front ends, and points having upper and lower surfaces at different angles and provided with shanks fitted to the last mentioned sockets. 50

3. In a beet harvester, a frame, standards thereon, extracting bars secured to the standards, said extracting bars having beveled upper edges at the front end forming tapered extensions, sleeves having sockets with upper and lower walls at different angles, said sockets being adapted to receive the ends of the extracting bars and to fit the upper and lower surfaces thereof, said sleeves having tapered sockets in their front ends, and points having upper and lower surfaces at different angles and provided with shanks, the upper and lower walls of which are of different pitch fitted to the last mentioned sockets. 60

4. In a beet harvester, extracting bars, means by which the said extracting bars are mounted, sleeves connected to the ends of the extracting bars, means whereby the angle of inclination of the sleeves may be changed 70 with relation to the extracting bars, points on the said sleeves, and means whereby the angle of inclination of the said points may be changed.

In testimony whereof, I affix my signature 75 in the presence of two witnesses.

ALFRED G. BIMSON.
